COLLAR CLAMPING APPARATUS

Harry D. Forse, Anderson, Ind.

Application May 9, 1946, Serial No. 668,407

8 Claims. (Cl. 223—52.1)

1

This invention relates to improvements in clamping apparatus, and more especially to collar clamping devices adapted to be used in conjunction with garment presses.

In pressing garments, as for instance, shirts or the like, it is customary and desirable to provide some means for securing the collar portion thereof as the yoke of the shirt is finished. Such clamping means are usually attached to the buck or lower stationary pressing member, with a portion thereof overlying the pressing surface and the head or upper movable pressing member is recessed to provide working clearance for the assembly.

Various types of clamping means have long been employed for the purpose of holding the collar clear of the pressing member and also to provide a reference point or target for laying the shirt preparatory to finishing the yoke thereof on a press. Some of the known hand operated clamping devices are those in which the structure is operated by the manipulation of a handle in the full grasp of an operator, or those in which operation is provided by finger tip control. In the operation of both of the foregoing types, the hands of an operator are required to be entirely removed from the work being smoothed or stretched upon the clamping device in order to operate the controls. Consequently, the clamped portion of the garment is often askew and misaligned relative to the device during the pressing operation. As a result of such misalignment the entire garment quite frequently has to be re-finished. Such re-working in addition to greatly increasing coats also slows production to considerable extent.

It is one of the chief objects of the present invention to overcome the imperfections of previous hand-operated clamps and to provide hand-operated clamping means which permit the full use of the fingers of both hands to hold taut and smooth the part to be clamped and concurrently with such operation to use the hands to move the improved device into clamping position.

A further object of advantage and importance resides in the provision of means for independently moving either of a pair of clamping means to or from clamping position. Additionally, such independent movement of the clamping means may be accomplished without the operator releasing the garment being clamped.

Still another object of advantage and importance is the provision of means for biasing the clamping members in either limit position, and

2

also of utilizing such biasing means to assist in moving the members to such limit positions.

Another object of importance and advantage of the improved device of this invention is the provision of means for automatically releasing both clamping members from clamped position upon operation of the press with which the device may be associated.

Additional objects of advantage and importance will become apparent as the following detailed description progresses, reference being had to the accompanying drawing, wherein:

Figure 1 is a front elevational view of a clamping apparatus which embodies the invention.

Figure 2 is a side elevational view thereof, shown associated with a fragmentary portion of a press.

Figure 3 is a front elevational view of the apparatus shown in clamped position, a portion thereof being broken away, and

Figure 4 is a top plan view of the apparatus with the parts thereof positioned as illustrated in Figure 1.

The reference numeral 10 indicates generally the improved clamping device of this invention. The device comprises a body 11, preferably although not necessarily, of hollow construction, and is shaped to conform to the desired contour of a finished collar. The front surface of the body 11 is offset and includes a downwardly and forwardly inclined intermediate portion 13, which terminates in securing bosses 12. The bosses 12 are located on opposed ends of the body 11, as is clearly shown in Figures 1 and 3. Formed in the flat upper surface of the body 11 and centrally thereof is a recess 14, which is adapted to provide clearance for an operating rod 16, later to be described.

Fixed to the undersurface of the body 11 and projecting therebelow is a pair of guide pins 18. The guide pins 18 are preferably secured to the bosses 12, as is best shown in Figure 1, and function to guide that member in its adjustable movement relative to the buck 24 and supporting member 20. The supporting member 20 extends rearwardly from the pins 18 and is provided with a plurality of elongated apertures 21 through which securing studs 22 and 23 extend. The studs 23 are adapted to be secured to the under portion of

a buck 24 with which the device is associated and lock nuts 25 operably associated with the studs 23 function to anchor and maintain the supporting member 20 rigid relative to the buck 24. A wing nut 26 operably associated with the stud 22 bears against the front lower surface of the sup-

porting member 20 and functions to draw the body 11 against the upper surface of the buck 24.

Pivots secured to the front upper portion of the body 11, preferably by socket head bolts 28, is a pair of bell crank members 30. The bell crank members 30 are spaced apart, as is best shown in Figures 1 and 3, and each is provided with a plurality of radially extending arms, indicated by the reference numerals 32, 34, and 36. The arms 32 extend upwardly and are turned upon themselves to form inverted substantially U-shaped members. The free end of each arm 32 is adapted upon rotation of the bell crank to be moved into and from engagement with the body 11, as is best shown by the positions of the member in Figures 1 and 3.

The arms 36 extend radially outwardly from a point diametrically opposite the members 32 and are flattened adjacent their free ends for use as operating handles. The arms 34 which are offset as at 35 extend radially outwardly from the central portion of each bell crank member 30 intermediate the arms 32 and 36. Secured in an outwardly extending portion 38 of each bell crank member 30 is a pin 40. The pins 40 are spaced radially from the socket head bolts 28 and are adapted when the bell crank member is in either limit position to be on a plane above or below a horizontal center line extending through the bell crank pivots. A helical spring 42 secured to the pins 40 provides a means for biasing the bell crank members 30 toward a limit position. It is to be noted that in the movement of the bell crank members 30 from one limit position to the other the spring 42 in being extended functions to yieldably resist such movement and as the pins 40 move past center the spring 42 in contracting functions to assist in the movement of the bell crank members 30.

Positioned above the device 10 and having one end thereof adapted to be secured to the movable head, not shown, of a press, is an operating rod 16. The lower end of the operating rod 16 is disposed to engage and operate the radially extending offset arms 34 to move the bell crank members 30 from clamped to open position. Lock nut 43 in screw-threaded association with the upper end of the operating rod 16 provides means for locking that member in selected adjustment relative to the head of the press. A pair of rollers 45 rotatably positioned on the lower end of the operating rod 16 provides an anti-friction engagement with the arms 34.

The supporting member 20 of the improved device of this invention may be adjusted horizontally or vertically as desired relative to the buck 24, to provide for the proper positioning of the body 11, and the operating rod 16 may be adjusted horizontally relative to the head, not shown, to cooperate with the arms 34. Thus, the device may be automatically operated at any selected position in the travel of the movable head.

Operation

When the improved device of this invention is operably associated with a press it may be operated substantially as follows:

The bell crank members 30 are moved to the position in which they are shown in Figure 1 and the yoke portion of a shirt is spread or laid upon the pressing member 24, with the collar thereof in engagement with the device 10. The operator then grasps a forward portion, or point, of the collar in each hand and draws it tautly about the body 11, thus bringing the ball portions of the

hand in close proximity to the flat portions of the arms 36. When the collar is properly aligned on the body 11 the operator moves both hands inwardly toward each other to engage the arms 36, thereby rotating the bell crank members and thus bringing the free ends of the arms 32 into clamping engagement with the collar against the body 11. It is to be noted that the operator may retain a hold on the collar during the clamping operation. Consequently, misalignment due to releasing the hold of one or both hands, as to operate a finger tip or other control device, is totally eliminated.

With the device in clamped position the pressing controls may be operated to bring the pressing members together in a finishing operation. The operating rod 16 may be adjusted to release the clamping mechanism during any portion of the finishing operation. For convenience, and by way of illustration, the rod 16 is illustrated as being set to release the clamping apparatus on the downward movement of the head. It will, therefore, be apparent that when the finishing operation is completed the improved clamping mechanism of this invention has been released so that the finished shirt or other garment may be readily removed from the press.

It will be apparent from the foregoing that herein is provided a simple and fool-proof clamping mechanism, comprising relatively few inter-related parts which may be economically manufactured and marketed. Moreover, the certainty with which garments may be precisely aligned through the use of the improved device of this invention, even when operated by unskilled persons having no previous experience, results in exceptional uniformity in the finished product.

As it will be apparent to those skilled in the art to which the improved device appertains that numerous changes and widely different embodiments of the invention may be made without departing from the spirit and scope thereof, it is intended that the embodiments shown in the drawing and description thereof shall be interpreted as illustrative only and not in a limiting sense. Reference is, therefore, to be had to the appended claims for a definition of the limits of the invention.

I claim:

1. In a garment press, a buck having a padded upper surface, a supporting plate adjustably secured to said buck remotely of the padded surface thereof, a collar clamp having a neck band receiving form, means adjustably securing said collar clamp to said supporting plate, said adjustable securing means being located to be operably adjusted when said press is in pressing or non-pressing position, a pair of members mounted for operable movement relative to said form, each of said members being provided with a portion adapted to be moved to and from engagement with said form, and mechanical means for moving said members from said form engaging position.

2. The structure of claim 1 including spring means yieldably maintaining said members in form engaging position, and guide means interposed between said supporting plate and collar clamp for maintaining said form in alignment with and immovable relative to the padded surface of the buck.

3. The structure of claim 1 including over center spring means operable to yieldably resist movement of said members in either direction and upon such movement being started to assist

in moving the members to their terminal positions, said supporting plate being secured to the lower external surface of said buck and being operable to support said form independently of the padded surface of said buck.

4. In a garment press, a buck having a resilient pressing surface, a collar clamp having a neck band receiving form, a pair of members mounted on said form for rotational movement between limit positions, spring means operable to bias said pair of members toward each limit position, a mechanical means for moving said pair of members from one limit position to the other limit position in unison, and means for maintaining said form stationary during the fluctuations of the resilient pressing surface of the buck caused by pressing operations.

5. The structure of claim 4 including means for detachably securing said form to a garment press.

6. In a garment press, a buck having a pressing surface, a collar clamp having a neck band receiving form, means for clamping the collar of a shirt to said form, said means comprising a pair of bell crank members rotatably secured to said form and having a portion on each operable upon rotation of said bell cranks to move into and from clamping association with said form, handle means projecting from each bell crank, biasing means operable upon rotational movement of said bell crank members to bias said members in an opposite rotational direction, and means lo-

cated remotely of the pressing surface of said buck for maintaining said collar clamp in operable association with said pressing surface.

7. The structure of claim 6 wherein the said handle means are formed and extend forwardly to be operated by the heel portions of the hands as the fingers thereof grasp and stretch a collar upon said form.

8. The structure of claim 6 wherein the said handle means are formed and extend forwardly below the rotational axes of said clamping means to be operated by the heel portions of an operator's hands as other portions thereof maintain a collar in association with said form, and means automatically operated for moving said bell cranks from clamping association with said form.
